UNITED STATES PATENT OFFICE.

DAVID F. HAYNES, OF BALTIMORE, MARYLAND.

DESIGN FOR A COVERED DISH.

SPECIFICATION forming part of Design No. 20,451, dated January 6, 1891.

Application filed November 28, 1890. Serial No. 372,981. Term of patent 3½ years.

To all whom it may concern:

Be it known that I, DAVID F. HAYNES, a citizen of the United States, residing at Baltimore, Maryland, have invented and produced a new and original Design for a Covered Dish, of which the following is a specification, reference being had to the accompanying drawings, forming a part hereof.

Referring to the said drawings, Figure 1 is an exterior side elevation of the covered dish, and Fig. 2 a top view of the same.

I describe the dish proper as follows: Its base A as seen from the under side is elliptical. The general form of the body B as seen from its top is elliptical; but it is divided into four sections *a* by contracting or drawing in the sides, as shown in Fig. 2. As seen from the side the body flares outward with a curved outline and then suddenly curves inward to the top or upper edge. The cover C as seen from the upper or lower side has the same outline as the body; but from the side it is semi-elliptical. In the center of the cover is a rosette formed of expanding flutes and leaves alternately arranged in relief. The cover is surmounted by a decorated semi-ellip-

tical handle D. The handles E of the body are on the longer diametrical line and they are suitably decorated, the design being in relief.

I claim as my invention—

30

1. The design for a covered dish herein shown and described, the same comprising the body having the general outline as seen from the top of an ellipse divided into four sections by contracting or drawing in the sides, the sides 35 flaring outward in curved lines and then suddenly curved inward, and provided with handles at the longer diametrical line, substantially as described.

2. The design for a covered dish herein described and shown, which comprises a cover having a general outline as seen from the top of an ellipse, with the same divided into four sections by contracting the sides, and semi-elliptical as seen from the side, the rosette 45 formed of alternate expanding flutes and leaves, and a handle, substantially as described.

DAVID F. HAYNES.
